Patented Nov. 12, 1974

233,615

PADDLE AND BALL TOY

Albert Stubbmann, Franklin Lakes, N.J., and Marie Louise Farber, New York, N.Y., assignors to Kohner Bros, Inc., East Paterson, N.J.

Filed Jan. 19, 1973, Ser. No. 324,950

Term of patent 14 years

Int. Cl. D21—01

U.S. Cl. D34—5 SP

FIG. 1.

FIG. 2.

FIG. 3.

FIG. 4.

FIG. 1 is a perspective view of a paddle and ball toy showing our new design;

FIG. 2 is a top plan view thereof;

FIG. 3 is an elevational view of the front thereof shown in FIG. 2; and

FIG. 4 is an elevational view of the side thereof shown in FIG. 2.

We claim:

The ornamental design for a paddle and ball toy, as shown.
